[57] CLAIM

The ornamental design for “a chairback slipcover”, as shown and described.

DESCRIPTION

FIG. 1 is a perspective view of a chairback slipcover showing my new design;

FIG. 2 is a front view thereof;

FIG. 3 is a top view thereof;

FIG. 4 is a side elevational view thereof, the opposite side being a mirror image of that shown;

FIG. 5 is a bottom view thereof; and,

FIG. 6 is a rear view thereof.

The cross-hatching represents conventional fabric and is understood to extend uniformly throughout the areas represented. The broken-line showing of environmental structure in FIG. 1 is for illustrative purposes only and forms no part of the claimed design.
